WEDGING PAWL TYPE WRENCH

Roy E. Gearhart, Kansas City, Mo., assignor of
one-half to Charles E. Hose, Kansas City, Mo.

Application October 3, 1949, Serial No. 119,346

10 Claims. (Cl. 192—45.1)

1

This invention relates to new and useful improvements in wrenches, and has particular reference to wrenches of the "clutch" or "ratchet" types, wherein nuts, bolts, or the like may be driven in one direction while the tool handle is moved reciprocally, without disengaging the tool from the work.

The principal object of the present invention is the provision of a wrench comprising a driving member, a driven member, a pawl carried movably by said driving member and adapted to engage said driven member operatively when said driving member is moved in one direction, and means for retracting said pawl out of engagement with said driven member when said driving member is moved in the opposite direction.

Another object is the provision of a wrench including a driving member, a driven member, a pawl disposed in floating relation between said driving and driven members and adapted to engage said driven member operatively, said pawl being driven by said driving member but having a period of lost motion relative thereto, and cam means carried by said driving member and operable during said period of lost motion to move said pawl into operative engagement with said driven member when said driving member is turned in one direction, and to move said pawl out of engagement with said driven member when said driving member is turned in the opposite direction.

A further object is the provision of a wrench which is noiseless in operation and has negligible drag or resistance to turning on its return strokes.

A still further object is the provision of a wrench of the class described having cam means for controlling the position of the pawl relative to the driven member, of means for adjusting said cam means whereby the wrench may be adapted to turn the work in either direction.

Other objects are the provision of a pawl having a large number of teeth in engagement with the driven member, whereby great strength is provided, the provision of a wrench having a minimum number of parts, economy and simplicity of construction, efficiency and dependability of operation, durability, and adaptability for use in various types of tools wherein an oscillating or "ratchet" drive is desired.

With these objects in view, as well as other objects which will appear in the course of the specification, reference will be had to the drawing, wherein:

Figure 1 is a side elevation of a wrench embodying the present invention, with parts broken away.

2

Figure 2 is a plan view of the head portion of the wrench shown in Fig. 1.

Figure 3 is an inverted plan view of the head portion of the wrench shown in Fig. 1.

5 Figure 4 is an enlarged fragmentary section taken on line IV—IV of Fig. 2.

Figure 5 is a section taken on line V—V of Fig. 4, showing the parts in the neutral position.

10 Fig. 6 is a view similar to Fig. 5, showing the parts positioned for a left-hand drive.

Fig. 7 is a view similar to Fig. 5, showing the parts positioned for a right-hand drive.

Fig. 8 is a view similar to Fig. 5, showing the parts positioned for a right-hand drive, but during 15 the return or rearward stroke of the handle.

Fig. 9 is a side elevation of a modification of the device adapted for use as a socket adapter for use with interchangeable extension handles, a representative extension handle being shown in dotted lines.

Fig. 10 is an enlarged section taken on line X—X of Fig. 9.

Like reference numerals apply to similar parts throughout the several views, and the numeral 2

25 applies to a hollow, cylindrical body member closed at one end by wall 4 and having an integral handle 6 extending radially therefrom. A square driving lug 8 is integral and coaxial with body member 2 and extends inwardly from the inner surface of wall 4. The planar surfaces of

30 said lug parallel to the axis of the body member are for convenience designated as side walls 10 and 12 and end walls 14 and 16. Said lug has an axial cylindrical bore 18 formed therethrough.

35 An annular setting plate 20 is disposed against the outer surface of wall 4, being carried for rotational oscillation on a cylindrical boss 22 extending outwardly from wall 4 coaxially with the body member. Said setting plate is held on said boss, and frictionally positioned relative to the

40 body member by a snap ring 24 which engages a peripheral groove 26 formed in boss 22. Said setting plate may be turned by means of a knurled handle 28 integral therewith. A pin 30 is fixed

45 in said setting plate and extends inwardly into body member 2 through an arcuate slot 32 formed in wall 4. Said pin is parallel with the axis of the body member and said slot is disposed concentrically to said axis. Said slot is disposed adjacent end wall 16 of driving lug 8, and is substantially coextensive therewith.

50 An annular pawl ring 34 fits rotatably within body member 4, and the inner surface of said ring is formed to present teeth 36 around the entire periphery thereof, said teeth extending parallel to the axis of the body member. The pawl ring

is closed at the end opposite body wall 4 by a wall 38. An axial stem 40 extends inwardly from wall 38 and is carried for rotation in bore 18 of lug 8. A headed screw 42 extends through boss 22 and wall 4 and is threaded into stem 40, thereby holding the body member and pawl ring in assembly. The head of said screw is countersunk in boss 22.

Wall 38 is formed to present an outwardly extending axial stem 44, preferably square in cross-section, adapted to fit into a correspondingly shaped hole 46 formed in an ordinary wrench socket member 48. Said socket member is retained on said stem by a detent ball 50 embedded in a recess 52 formed in stem 44 and urged outwardly by a spring 54 carried in said recess. Said ball is adapted to engage a recess 56 formed in the wall of hole 46. Socket member 48 has a non-circular recess 58 formed in its outer end for engaging nuts, bolt heads, and the like. Said socket members are usually sold in sets, having work engaging recesses of graduated sizes and different shapes. This type of socket, as well as its mounting, is common and no claim is made specifically thereto. The pawl ring 34 could, of course, be extended outwardly from the body member, and the work engaging recess 58 formed directly therein, without departing from the spirit of the invention.

A flat, roughly circular pawl 60 is carried within pawl ring 34, fitting slidably between body member wall 4 and pawl ring wall 38, as best shown in Fig. 4. A roughly rectangular hole 62 is formed centrally through said pawl, into which square driving lug 8 and pin 30 extend. Referring principally to Figs. 5 to 8, it will be noted that the side walls of hole 62, or those walls adjacent side walls 10 and 12 of lug 8, are each formed of two planar sections converging inwardly to an obtuse angle substantially at the transverse axis of the hole. Thus relatively angled walls 64 and 66 are formed adjacent lug wall 10 and walls 68 and 70 are formed adjacent lug wall 12, wall 64 being parallel to wall 10 and wall 66 being parallel to wall 68. The end wall of hole 62 adjacent end wall 14 of lug 8 is provided with a central section 72 parallel to the transverse axis of the hole and end sections 74 and 76 inclined relatively outwardly, wall 74 being at right angles to wall 66 and wall 76 being at right angles to wall 70.

The portion of the outer periphery of pawl 60 corresponding to and substantially coextensive with wall 72—74—76 of hole 62 is formed to present teeth 78 adapted to engage teeth 36 of pawl ring 34. The pawl is adapted to move within pawl ring 34 longitudinally to hole 62 either into engagement with the pawl ring, as shown in Figs. 6 and 7, or out of engagement therewith as shown in Figs. 5 and 8. When retracted out of engagement with said pawl ring, wall 72 of hole 62 rests against wall 14 of lug 8. The wall of hole 62 opposite wall 72—74—76, and adjacent lug wall 16, is formed to present an arcuate central section 80 having a radius of curvature equal to the radius of movement of the outer edge of pin 30, and outwardly inclined cam sections 82 and 84 at the ends of said arcuate section. Cam wall 84 is slightly divergent inwardly from wall 76, and cam wall 82 is likewise divergent from wall 74, in order that lug 8 and pin 30 may turn as a unit within hole 62 of the pawl without binding. A leaf spring 86 is fixed at one end in pawl 60, and bears resiliently against the toothed inner surface of pawl ring 34 diamet-

rically opposite the toothed portion of said pawl. This spring urges the pawl toward engagement with the pawl ring, and provides a brake resisting the rotation of the pawl in the pawl ring. Pawl 60 is provided at its outer periphery with rounded projections 88 substantially on the transverse axis of hole 62. These projections serve to prevent undue transverse movement of the pawl relative to lug 8.

The operation of the wrench is substantially as follows: Referring to Fig. 5, which shows the parts in the neutral position, it will be noted that pin 30 has been moved to the central part of slot 32 by means of handle 28. In this position pin 30 engages arcuate wall 80 of pawl hole 62 to retract pawl 60 out of engagement with pawl ring 34. It will be noted that wall 80 coincides with the path of the outer edge of pin 30, and that wall 72 of pawl hole 62 is held against wall 14 of lug 8. The pawl is thus held out of engagement with the pawl ring, and is locked against rotation on lug 8, and handle 6 may be rotated freely in either direction without causing the pawl to engage the pawl ring.

To provide a left-hand drive, handle 28 is turned to move pin 30 to the lower end of slot 32, as shown in Fig. 6, said pin then resting substantially at the junction of arcuate wall 80 and cam wall 84 of the pawl. Handle 6 is then turned in the direction indicated by the arrow in Fig. 6, thereby causing lug 8 to turn in pawl hole 62. As this turning occurs, lug wall 14, contacting the pawl at the juncture of walls 12 and 76 of said pawl, cams the pawl transversely to the axis of the wrench to move the teeth 78 thereof into engagement with teeth 36 of the pawl ring. During this transverse movement of the pawl, pin 30 rides along cam wall 84 of the pawl, the outward inclination of said wall permitting transverse movement of the pawl. The parts are so proportioned that at the same time that the pawl and pawl ring reach full engagement, wall 14 of lug 8 comes into planar contact with wall 76 of the pawl hole, and the side walls 10 and 12 of the lug respectively contact walls 64 and 70 of the pawl hole. Spring 86 also assists in moving the pawl into engagement with the pawl ring. The parts then have the relation shown in Fig. 6, and the wrench is adapted for a left-hand drive. The torque applied to driving lug 8 by handle 6 is applied to pawl 60 by the engagement of walls 64 and 70 of said pawl against walls 10 and 12 of said lug, is transferred to pawl ring 34 by said pawl, and thence to wrench socket 48. The engagement of lug wall 14 with wall 76 of the pawl holds the pawl firmly in engagement with the pawl ring, and also imparts rotational torque to the pawl.

Fig. 7 shows the parts correspondingly positioned for a right-hand drive. Pin 30 has been moved to the upper end of slot 32, and handle 6 turned in the direction indicated by the arrow. Lug walls 10 and 12 bear respectively against walls 66 and 68 of the pawl, and lug wall 14 bears against wall 74 of the pawl. It will be noted that in neither the right or left-hand drives does pin 30 support any of the load.

Fig. 8 shows the parts positioned for a right-hand drive, but during the rearward or "ratcheting" stroke of handle 6. If, with the parts in the driving position as shown in Fig. 7, handle 6 is turned in a reverse direction as indicated by the arrow in Fig. 8, lug 8 and pin 30 will turn as a unit about the axis of the wrench, and pin 30, acting on cam wall 82 of the pawl,

will cam the pawl out of engagement with pawl ring 34. When the pin reaches the juncture between cam wall 82 and arcuate wall 80, as in Fig. 8, the pawl is fully retracted, wall 72 thereof resting against lug wall 14. The pawl is thereby secured against further rotation relative to the lug and handle 6 may be turned freely. When the direction of rotation of handle 6 is again reversed, the pawl will be cammed into engagement with pawl ring 34 by lug 8 as previously described.

From a consideration of Figs. 6 and 7, it is apparent that when pin 30 is disposed at either end of slot 32, and pawl 60 is in engagement with the pawl ring, pin 30 cannot be moved in slot 32, due to the fact that one or the other of cam walls 82 and 84 of the pawl extend across the path of said pin. For this reason, in order to adjust pin 30 in slot 32 by means of handle 28, it is first necessary to back handle 6 slightly to move pawl 60 to its retracted position, as shown in Fig. 8. Pin 30 may then be freely adjusted with handle 28. This feature prevents accidental movement of the pin when a load is being applied by the wrench, which would of course retract the pawl.

Since pawl 60 is positively cammed both into and out of engagement with the pawl ring, it is apparent that the wrench would function properly in most circumstances even if spring 66 were omitted, the pawl having sufficient inertia to resist rotation as it is cammed laterally by lug 8 and spring 39. However, the spring is effective to provide a slight braking action on the rotational movement of the pawl relative to the pawl ring, thereby holding the pawl against rotation as it is cammed laterally. This provides a more positive pawl action, preventing "skipping" of teeth as the pawl moves into engagement, and reduces the lost motion of the handle to a minimum. The strength of said spring, however, is not sufficiently large to cause any appreciable drag on handle 6 as said handle moves through its return or "ratcheting" strokes. Suitable indicia 98 may be imprinted on the outer surface of body wall 4, as shown in Fig. 2, for cooperating with handle 28 to indicate the position of pin 30.

In the modified form shown in Figs. 9 and 10, the body member 2 does not have an integral handle. Instead, body wall 4 is provided with an outwardly extending axial boss 92, corresponding to boss 22 of the preferred form, said boss having a squared recess 94 in its outer end for receiving the correspondingly shaped end of any of various types of extension handles for driving the wrench. A representative type of handle 96 is shown in dotted lines in Fig. 9. The setting plate 98, which corresponds to setting plate 20 of the preferred form, is of slightly longer diameter than body member 2 and has its edge knurled for easy turning. An indicator finger 100 is carried by said plate and cooperates with indicia 102 imprinted on body member 2 to indicate the setting of pin 30. The construction and operation of the modified wrench is otherwise identical with that of the preferred form.

Thus it is apparent that a wrench having several advantages has been produced. It is extremely simple and economical, having only three moving parts carried by the body member. It has a minimum of lost motion, and is noiseless in operation. It is efficient and dependable in operation, and not likely to get out of order. The bodily transitional movement of the pawl, in distinction to the usual pivotal mounting of ratchet pawls, permits the use of a pawl having a large

number of teeth, thereby providing an exceptionally strong tool. Breakage or damage of a portion of the pawl teeth will not appreciably impair the efficiency of the wrench.

While I have shown specific embodiments of my invention, it is apparent that many minor variations of construction and operation could be made without departing from the spirit of the invention.

What I claim as new and desire to protect by Letters Patent is:

1. A wrench comprising a manually rotatable body member, a pawl ring carried for coaxial rotation by said body member, a work engaging member carried by said pawl ring, a pawl carried by said body member for movement to and from engagement with said pawl ring transversely to the axis thereof, said body member having a limited degree of rotational lost motion relative to said pawl, and cam means carried by said body member and operable during said lost motion to move said pawl into engagement with said pawl ring when said body member is turned in one direction, and to move said pawl out of engagement with said pawl ring when said body member is turned in the opposite direction, said cam means being adjustable relative to said body member whereby rotation of said body member will cause said pawl ring to be driven selectively in either direction.

2. A wrench comprising a manually rotatable body member, a pawl ring carried for coaxial rotation by said body member, a work engaging member carried by said pawl ring, a pawl carried by said body member for movement to and from engagement with said pawl ring transversely to the axis thereof, said body member having a limited degree of rotational lost motion, relative to said pawl, cam means carried by said body member and operable during said lost motion to move said pawl into engagement with said pawl ring when said body member is turned in one direction, and to move said pawl out of engagement with said pawl ring when said body member is turned in the opposite direction, frictional means resisting rotation of said pawl relative to said pawl ring, and means for adjusting said cam means whereby said pawl may be caused to drive said pawl ring in either direction or retracted to a neutral position out of engagement with said pawl ring.

3. A wrench comprising a body member, manual means for rotating said body member, a non-circular driving lug carried rigidly by said body member in its axis of rotation, an internally toothed pawl ring carried rotatively by said body member concentrically about said driving lug, a work engaging member carried by said pawl ring, a planar pawl having a hole formed therein fitting over said lug and having a portion of its periphery toothed for engagement with said pawl ring, said hole being proportioned to permit limited rotational movement of said lug therein and movement of said pawl transversely to the axis of rotation to and from engagement with said pawl ring, said lug being adapted when turned in one direction within said pawl to contact a wall of said hole to move said pawl into engagement with said pawl ring, and a cam member carried by said body member and operable as said lug is turned in the opposite direction within said pawl to contact a wall of said hole to move said pawl out of engagement with said ring.

4. A wrench comprising a body member, manual means for rotating said body member, a

non-circular driving lug carried rigidly by said body member in its axis of rotation, an internally toothed pawl ring carried rotatively by said body member concentrically about said driving lug, a work engaging member carried by said pawl ring, a planar pawl having a hole formed therein fitting over said lug and having a portion of its periphery toothed for engagement with said pawl ring, said hole being proportioned to permit limited rotational movement of said lug therein and movement of said pawl transversely to the axis of rotation to and from engagement with said pawl ring, said lug being adapted as it is turned to either limit of its rotation relative to said pawl to contact a wall of said hole to move said pawl into engagement with said pawl ring, whereby said pawl ring is driven, and a cam member carried by said body member and operable when said lug is backed away from one of said driving positions to move said pawl out of engagement with said pawl ring.

5. A wrench comprising a body member, manual means for rotating said body member, a non-circular driving lug carried rigidly by said body member in its axis of rotation, an internally toothed pawl ring carried rotatively by said body member concentrically about said driving lug, a work engaging member carried by said pawl ring, a planar pawl having a hole formed therein fitting over said lug and having a portion of its periphery toothed for engagement with said pawl ring, said hole being proportioned to permit limited rotational movement of said lug therein and movement of said pawl transversely to the axis of rotation to and from engagement with said pawl ring, said lug being adapted as it is turned to either limit of its rotation relative to said pawl to contact a wall of said hole to move said pawl into engagement with said pawl ring, whereby said pawl ring is driven, a cam member carried by said body member and operable when said lug is backed away from one of said driving positions to move said pawl out of engagement with said pawl ring, and means for adjusting said cam member whereby the retraction of the pawl may be caused to drive said pawl ring selectively in either direction.

6. A wrench comprising a body member, manual means for rotating said body member, a non-circular driving lug carried rigidly by said body member in its axis of rotation, an internally toothed pawl ring carried rotatively by said body member concentrically about said driving lug, a work engaging member carried by said pawl ring, a planar pawl having a hole formed therein fitting over said lug and having a portion of its periphery toothed for engagement with said pawl ring, said hole being proportioned to permit limited rotational movement of said lug therein and movement of said pawl transversely to the axis of rotation to and from engagement with said pawl ring, said lug being adapted as it is turned to either limit of its rotation relative to said pawl to contact a wall of said hole to move said pawl into engagement with said pawl ring, whereby said pawl ring is driven, a cam member carried by said body member and operable when said lug is backed away from one of said driving positions to move said pawl out of engagement with said pawl ring, means for adjusting said cam member whereby the retraction of the pawl may be caused to drive said pawl ring selectively in either direction, and braking means resisting rotation of said pawl in said pawl ring.

7. A wrench comprising a body member, a handle for rotating said body member, a square driving lug carried rigidly by said body member in its axis of rotation, an internally toothed pawl ring carried for coaxial rotation by said body member about said lug, a work engaging member carried rigidly by said pawl ring, a planar pawl carried within said pawl ring and having a portion of the outer edge thereof toothed for engagement with said pawl ring, said pawl having a roughly rectangular hole formed therethrough and fitting over said driving lug, the major axis of said hole intersecting the toothed portion of said pawl to permit movement of said pawl transversely to the axis of the body member to and from engagement with said pawl ring, a spring urging said pawl into engagement with said pawl ring, the side walls of said hole being formed to permit limited rotation of said lug therein, said lug being adapted when turned to either limit of its rotation in said hole to contact the end wall of said hole adjacent the toothed portion of the pawl, and a cam pin carried by said body member and projecting into said hole parallel with the axis of the body member, said pin contacting the opposite end wall of said hole, said last named wall being formed to present cam surfaces which are engaged by said pin when the driving lug is backed away from one of said driving positions to move said pawl out of engagement with said pawl ring.

8. A wrench comprising a body member, a handle for rotating said body member, a square driving lug carried rigidly by said body member in its axis of rotation, an internally toothed pawl ring carried for coaxial rotation by said body member about said lug, a work engaging member carried rigidly by said pawl ring, a planar pawl carried within said pawl ring and having a portion of the outer edge thereof toothed for engagement with said pawl ring, said pawl having a roughly rectangular hole formed therethrough and fitting over said driving lug, the major axis of said hole intersecting the toothed portion of said pawl to permit movement of said pawl transversely to the axis of the body member to and from engagement with said pawl ring, a spring urging said pawl into engagement with said pawl ring, the side walls of said hole being formed to permit limited rotation of said lug therein, said lug being adapted when turned to either limit of its rotation in said hole to contact the end wall of said hole adjacent the toothed portion of the pawl, and a cam pin carried by said body member and projecting into said hole parallel with the axis of the body member, said pin contacting the opposite end wall of said hole, said last named wall being formed to present an arcuate central section which is concentric with the body member when the pawl is in its retracted position, and an outwardly inclined planar cam section at each end of said arcuate section, said pin resting on one of said cam sections when said lug is in driving position, whereby when said lug is backed away from its driving position said pin will cam said pawl out of engagement with said pawl ring.

9. A wrench comprising a body member, a handle for rotating said body member, a square driving lug carried rigidly by said body member in its axis of rotation, an internally toothed pawl ring carried for coaxial rotation by said body member about said lug, a work engaging member carried rigidly by said pawl ring, a planar pawl carried within said pawl ring and having a por-

tion of the outer edge thereof toothed for engagement with said pawl ring, said pawl having a roughly rectangular hole formed therethrough and fitting over said driving lug, the major axis of said hole intersecting the toothed portion of said pawl to permit movement of said pawl transversely to the axis of the body member to and from engagement with said pawl ring, the side walls of said hole being formed to permit limited rotation of said lug therein, said rotation being 10 symmetrical with respect to the longitudinal axis of said hole, the end wall of said hole adjacent the toothed portion of said pawl having a central planar section parallel with the minor axis of the hole and adapted to lie flat against the corresponding wall of said lug when said pawl is in its retracted position and outwardly inclined planar end sections which respectively lie against said lug wall when the lug is turned to the limits of its rotation in said pawl, the opposite end wall 20 of said hole having a central arcuate section which is concentric with the body member when the pawl is in its retracted position and outwardly inclined planar end sections, a cam pin carried by said body member and projecting into said pawl hole parallel to the axis of said body member to ride on said last named end wall of said pawl hole, and means for adjusting said pin concentrically about the axis of said body member between fixed limits, said limits corresponding to 30 the ends of the arcuate wall section of said pawl hole when said pawl is in its retracted position.

10. A wrench comprising a body member, a handle for rotating said body member, a square driving lug carried rigidly by said body member 35 in its axis of rotation, an internally toothed pawl ring carried for coaxial rotation by said body member about said lug, a work engaging member carried rigidly by said pawl ring, a planar pawl carried within said pawl ring and having a portion of the outer edge thereof toothed for engagement with said pawl ring, said pawl having a roughly rectangular hole formed there-

through and fitting over said driving lug, the major axis of said hole intersecting the toothed portion of said pawl to permit movement of said pawl transversely to the axis of the body member to and from engagement with said pawl ring, the side walls of said hole being formed to permit limited rotation of said lug therein, said rotation being symmetrical with respect to the longitudinal axis of said hole, the end wall of said hole adjacent the toothed portion of said pawl having a central planar section parallel with the minor axis of the hole and adapted to lie flat against the corresponding wall of said lug when said pawl is in its retracted position and outwardly inclined planar end sections which respectively lie against said lug wall when the lug is turned to the limits of its rotation in said pawl, the opposite end wall of said hole having a central arcuate section which is concentric with the body member when the pawl is in its retracted position and outwardly inclined planar end sections, a cam pin carried by said body member and projecting into said pawl hole parallel to the axis of said body member to ride on said last named end wall of said pawl hole, means for adjusting said pin concentrically about the axis of said body member between fixed limits, said limits corresponding to the ends of the arcuate wall section of said pawl hole when said pawl is in its retracted position, and a frictional braking means resisting the rotation of said pawl relative to said pawl ring.

ROY E. GEARHART.
